(57) **CLAIM**

The ornamental design for a monitor for automobile, as shown and described.

DESCRIPTION

FIG. 1 is a front perspective view of the monitor for automobile in accordance with the new design.

FIG. 2 is a front view thereof;

FIG. 3 is a rear view thereof;

FIG. 4 is a left side view thereof;

FIG. 5 is a right side view;

FIG. 6 is top plan view thereof;

FIG. 7 is a bottom plan view thereof; and,

FIG. 8 is a rear perspective.

The broken lines shown in FIGS. 1–8 represent portions of the monitor for automobile and form no part of the claimed design.

1 Claim, 6 Drawing Sheets
